UNITED STATES PATENT OFFICE.

FREDERICK B. ETHER, OF RICHMOND HILL, NEW YORK.

DESIGN FOR A SMOKER'S STAND OR SIMILAR ARTICLE.

Application filed November 8, 1928. Serial No. 28,797. Term of patent 7 years.

To all whom it may concern:

Be it known that I, FREDERICK B. ETHER, a citizen of the United States, and a resident of Richmond Hill, county of Queens, State of New York, have invented a new, original, and ornamental Design for Smoker's Stand or Similar Article, of which the following is a specification, reference being had to the accompanying drawing, forming part thereof.

The drawing is a perspective view of a smoker's stand or similar article showing my new design.

I claim:

The ornamental design for a smoker's stand or similar article, as shown.

FREDERICK B. ETHER.
